UNITED STATES PATENT OFFICE.

FRANK FINK, OF SPRINGFIELD, OHIO.

OIL-CUP.

SPECIFICATION forming part of Letters Patent No. 309,839, dated December 30, 1884.

Application filed July 22, 1884. (No model.)

To all whom it may concern:

Be it known that I, FRANK FINK, of the city of Springfield, county of Clark, and State of Ohio, have invented certain new and useful Improvements in Oil-Cups, of which the following is a specification.

This invention relates to oil-cups, and has for its object to provide an oil-cup wherein the valve-seat is located in the cap of the cup, and wherein the valve-stem is hollow and provided with outlet-ports, to allow the oil to be poured into the cup through the stem of the valve, said stem extending out through the cup, thereby preventing dirt and dust from entering the cup when the valve is normally closed, and permitting the valve to be operated from the outside of the cup.

My invention consists in an oil-cup provided with a screw-cap having a valve-seat, in combination with a valve having a stem provided with a central opening in the direction of its length, and outlet-ports in communication therewith, said stem extending through the cap of the cup, and being provided with springs to retain it in a desired position, substantially as hereinafter described.

It also consists in the combination, with an oil-cup having a removable cap provided with a valve-seat, of a valve having a hollow stem extended through the removable cap, said stem being provided with a concaved head, and having outlet-ports in communication with the central opening of the valve-stem, and a spring to keep the valve normally seated, substantially as and for the purpose hereinafter described.

It also consists in an oil-cup having a removable cap provided with a valve-seat, in combination with a valve the stem of which is provided with a central opening and outlet-ports, said outlet-ports communicating with the central opening, and being so located upon the stem as to be closed when the valve is seated, and having air-vent openings communicating with the outer atmosphere, said air-vents being cut into the valve-stem at its periphery, substantially as hereinafter described.

It also consists in the combination, with an oil-cup having a cap provided with a valve-seat and a central opening, of a valve-stem provided with a removable valve at its lower

end and a concaved cap at its upper end, and having a central opening and outlet-ports communicating therewith, and having air-vents communicating directly with the outlet-ports, to allow air to enter the ports at a point in close proximity thereto, the said valve-stem being provided with a spring, said spring being located between the concaved head of the stem and the cap of the oil-cup, to keep the valve normally closed, substantially as hereinafter described.

Figure 1 represents in side elevation an oil-cup constructed in accordance with my invention, and Fig. 2 a longitudinal section of the same.

The base A of the oil-cup, of usual material, is provided with the oil-chamber B and outlet port or opening C, and is of ordinary construction. The cap D, provided with screw-threads, and adapted to be screwed into the base or main portion of the oil-cup, is hollowed out at its interior, and has a depending valve-seat portion, E, which forms the seat for the valve F, said valve F being provided with a valve-stem, G, which is preferably screwed into the valve. (See Fig. 2.) The valve-stem G is provided with a central opening, H, which extends a portion of its length and communicates with outlet-ports I, which ports are provided with external air-vents, J, which normally extend to a point just above the cap D. The valve-stem G is extended out through the central opening of the cap D, said cap forming a bearing therefor, and is provided at its upper end with a concaved head, K, said concavity converging toward the central opening, H, of the valve-stem.

Located upon the valve-stem G, and between its head K and the cap D of the oil-cup, is a spiral spring, L, which keeps the valve F pressed normally against its valve-seat.

By the construction herein described I am enabled to turn oil into the oil-cup through the valve-stem, it being simply necessary to press the stem and valve down, so that the outlet-ports may come to a point below the valve-seat, the air-vents allowing air to pass into the oil-receptacle.

The operation of manipulating the valve from the outside and doing away with a screw-threaded valve-stem is a great advantage.

I am aware that oil-cups have been in use wherein the valve-stem was provided with a head to abut against the cap of the oil-cup upon its interior to keep the dust from entering the cup, said stem being also provided with a spring; but such valve-stem and valve were inconvenient to operate and more expensive to manufacture.

The air-vents J are made by cutting a channel or groove into the valve-stem from the outlet-ports I to a point above the cap D of the oil-cup.

I claim—

1. An oil-cup provided with a screw-threaded cap having a valve-seat, in combination with a valve having a stem provided with a central opening in the direction of its length, and outlet-ports in communication therewith, said stem extending through the cap of the cup, and being provided with springs to retain it in place, substantially as and for the purpose described.

2. The combination, with an oil-cup having a removable cap provided with a valve-seat, of a valve having a hollow stem extending through the removable cap, said stem being provided with a concaved head, and having outlet-ports in communication with its central opening, and a spring located between the head of the valve-stem and oil-cup to keep the valve normally seated, all as and for the purpose described.

3. An oil-cup having a removable cap provided with a valve-seat, in combination with a valve the stem of which is provided with a central opening and outlet-ports, said outlet-ports communicating with the central opening, and being so located upon the stem as to be closed when the valve is seated, as described, and having air-vent openings, said air-vent openings being cut into the valve-stem at its outside, substantially as and for the purpose set forth.

4. The combination, with an oil-cup having a removable cap provided with a valve-seat, and having a central opening, of a smooth-surfaced valve-stem provided with a removable valve at its lower end, a concaved cap at its upper end, and a central opening and outlet-ports, said ports being provided with air-vents communicating directly therewith to allow air to enter the oil-cup below the surface of the cap, the said valve-stem being provided with a spring located between its head and the cap of the oil-cup to keep the valve normally closed; substantially as described.

In witness whereof I have hereunto set my hand and seal, at Springfield, Ohio, this 18th day of July, A. D. 1884.

FRANK FINK. [L. S.]

In presence of—

N. E. C. WHITNEY,
P. J. CLEVENGER.
